UNITED STATES PATENT OFFICE.

GEORGE A. TAYLOR, OF MUNCIE, INDIANA.

FIRELESS STOVE.

Application filed February 19, 1920. Serial No. 359,828.

To all whom it may concern:

Be it known that I, GEORGE A. TAYLOR, citizen of the United States, residing at Muncie, in the county of Delaware and State 5 of Indiana, have invented certain new and useful Improvements in Fireless Stoves, of which the following is a specification.

This invention relates to improvements in fireless stoves of the type which consists of 10 an outer case, and an inner case, with heat insulating material interposed; the container so provided being intended to maintain the temperature of the article placed therein.

15 To provide a fireless stove by which the temperature of the materials placed therein may be maintained, and in which the actual cooking of foods may be accomplished, are the objects of this invention, and 20 it consists of the new construction, combination and arrangement of parts and the features of improvement, shown in the annexed drawings, and described in the present specification. The invention is defined 25 in the appended claims.

The several parts of the invention are identified by suitable characters of reference applied thereto in the different views in the drawings, in which—

30 Figure 1 is a perspective view of one of my improved fireless stoves, the "two-well" size.

Figure 2 is a frontal view, portions thereof being broken away and one end of the device being shown in central longitudinal section.

Figure 3 is an end view of Figure 1, the lid or closure plate of the stove being at closed position.

40 Figure 4 is a top plan view of the stove, a portion on the top plate, and of the cover lids being broken away.

Figure 5 is an enlarged detail view of the vent device.

45 Figure 6 is a transverse vertical sectional view of the lid.

My present invention is embodied in the preferred form and construction shown. In the model illustrated, namely—the "two 50 well" size, the body may be thirty inches in length, fourteen inches wide, and fifteen inches in height. This box shaped body comprises a sheet metal wall plate having the side portions A, A, and the end portions 55 B and B. The top plate C made of sheet metal, preferably aluminum, and provided

with circular openings, has its edges secured to the top edges of the side plates A, A, and the end plates B and B. O designates the bottom plate. Each of the cylindrical wells 60 D, made of sheet metal, preferably aluminum, has its rim secured to the edge of the circular opening in the top plate C. Adapted to reside immediately in contact with the bottom of the well D is a sheet metal disk 65 E. This disk may be made of steel or other metal and its function is to form a reinforcement for the bottom of the well cylinder. To avoid electro-chemical activity between the two metals, this disk is subjected to a 70 coating of asphaltum or other electrical insulating compound.

The frame for the aforesaid sheet metal body consists of a combination of wooden strips F, G, and H, suitably connected together and adapted to brace and stiffen the sheet metal sides A and the end plates B. 75

In completing the assembly of the several parts constituting my improved fireless stove, the structure just described, is disposed at inverted position on the worker's bench; cylindrical sleeves K of sheet metal are then disposed at position, the rims K¹ of same being disposed at contact with the underside of the top plate C. The sheet 80 metal disks E are disposed at place in contact with the bottoms of the well cylinders D and D. It will be observed that the diameter of the sleeve K is sufficiently greater than that of the well cylinder D that the 85 space I is provided, and in which the non-circulating air so contained, is the insulating medium. Additional insulation between the sleeve K and the wall plates, consists of a wrapping L made of a succession of layers 90 of corrugated or cellular paper or composition, and which wrapping fills the space between the sleeves K and the wall plates, and being retentive of the air, constitutes effective insulation for the well cylinders. It 95

is contemplated that cellular tissue of other material may be used, the object being to have an air space therein partitioned in such manner that any circulation of the air so confined, is prevented, and such air constitutes the main medium of insulation. The corner spaces of the body are then packed tightly with excelsior M or other suitable resilient light packing material.

Immediately at contact with the disk E is 110 placed a filling of fireproof material such as mineral wool N, and it insures proper insu-

lation against the heat from the well cylinder bottom and the disk. The bottom plate O is then placed at position it being secured by suitable means, to the frame members, then joined to the bottom edges of the side plates A and A and the end plates B and B. Closure members or lids hingedly connected to the top edge of the side plate A are adapted to close the well openings. In order that this lid, when secured at the closed position by suitable means such as the cam latch Q may hermetically close the well, the construction of the said lid is as follows; the cross shaped wooden frame P has the recesses P¹; the metal top plate P² has the bottom edges of its vertical sides crimped to retain the edges of the metal bottom sheet P³ which is secured at place after the insulating material which may be of corrugated paper or other cellular tissue R will have been stuffed in the spaces between the members of the frame P and in the recesses P¹. A sufficient amount of insulating material is used so that when the plate P³ will have been secured, it will have a slightly bulged or convex contour; the insulating material acting as a cushion. The effect of such construction and arrangement of parts, is, that when the lid is at closed position, the securing it by the cam latch, causes the bottom plate P³ of the lid to snugly engage the rim edge of the well cylinder, the staunch support of the top plate being assured by the sleeves K. By the construction, combination and arrangement of parts shown and described, is provided a body and closure means, by which the temperature of the article placed in the well may be maintained for an indefinite length of time. In addition to the economies available in the factory construction and assembling of the parts making up the complete invention, there is the important and valuable feature of the provision of the non-circulatory air space immediately adjacent to the wall of the well cylinder; the arrangement of the sleeve K for this purpose and which extends from the bottom plate O to the underside of the top plate C and supports the top plate C, in turn, constitutes the internal wall making practicable the use of a cellular packing material. This cellular packing material is desirable for the reason that while filling the space between the sleeve and the wall plates, there is lightness in weight, and also ample space for air insulation, and a confining of the air that is retained therein in such manner that its full efficiency as an insulating medium is obtained. A fireless stove constructed in accordance with my invention has all of the advantages of rugged durability, minimum weight, and a maximum efficiency in retaining the temperature that may be created in the well cylinders; moreover it is free

from all hazards of fire or combustion. While this fireless stove, as a device to maintain the temperature of articles placed therein, may be used for the purpose of maintaining temperatures of low degree, the use to which it is especially adapted and intended, is that of a stove or cooking device. In its use as such cooking device there may be used a heat retaining member which may consist of soap stone or other heat retaining material. This heat retaining member is placed in the bottom of the well, there being interposed a support plate 2. This support plate 2 has the feet 2^a whereby the plate is maintained a distance above the bottom of the well to afford air circulation. A container 3, closed, and in which is retained the food, is then disposed in the well and on the heated member. The lid being then closed down and secured, the process of cooking ensues.

To afford egress of the gases proper to be discharged from the well during the cooking, is provided the vent arrangement shown in Figure 5. Centrally of the closure lid frame P and the bottom plate P³ is provided the vertical tube S that has the internal annular seat S¹. On this seat rests a ball T. In the upper mouth of the tube S is the close fitting tubular shell U in whose lower edge is provided the small recess U¹. The parts above described are so proportioned and the ball T is of such diameter and weight that the device is operative at the correct time of release of such pressure as may be generated in the well. By providing this simple means of pressure relief, all of the advantages of the fireless stove are retained, and at the same time there is prevented all possible tendency of escapement of steam around the rim edges of the well. When the pressure of gas in the well is sufficient to raise the ball T, there is the free escapement through the tubular shell U. The ball T coming into contact with the bottom of shell U limits the amount of escapement, the maintenance of temperature in the well being not impaired; the escapement however is not entirely stopped for the reason that although the ball may bear against the bottom of shell U, there are the small openings U¹ that permit escapement.

What I claim as my invention, and desire to secure by Letters Patent, is—

1. A fireless stove, comprising a box-shaped body, a top plate, a tubular sleeve extending upwardly from the bottom plate to the underside of the top plate, a sheet metal disk electrically insulated, to fit in and slightly above the bottom of the said tubular sleeve, a fireproof insulation between the disk and the bottom plate of the body, heat insulating material surrounding the tubular sleeve, packing material stuffed between the insulating material and the body, a cy-

lindrical container inside and of diameter less than that of the tubular sleeve and having its upper rim opening through the said top plate, and a closure plate for the said 5 opening.

2. A fireless stove, comprising a box shaped body, a top plate, an open sleeve extending from the bottom of the body to the top plate of the body, a metal plate to fit 10 in and slightly above the bottom of the said sleeve, fireproof insulation between the said plate and the bottom plate of the body, heat insulating material surrounding the said sleeve, a container inside said sleeve and 15 having its upper end opening through the top plate, said container being of a diameter less than the diameter of said sleeve and to provide an air space between the container and the sleeve, and a closure lid for 20 said container.

3. A fireless stove, comprising a box shaped body, a top plate, a tubular sleeve extended upwardly from the bottom plate to the undersurface of the top plate, the 25 lower end of the sleeve being cone shaped, a sheet metal disk electrically insulated and of diameter to be wedged into tightened position in the coneshaped portion of the tubular sleeve and slightly above the bottom 30 of the tubular sleeve, a container of diameter less than that of the tubular sleeve, fireproof material between the disk and the bottom plate of the body, layers of cellular insulating material between the sleeve and the walls 35 of the body, and packing between the cellular insulating material and the walls of the body.

4. A fireless stove, comprising a box shaped body, a top plate, an open sleeve

extending from the bottom plate to the underside of the top plate of the body, a metal plate to fit in and slightly above the bottom of the said sleeve, fireproof insulation between the said metal plate and the bottom plate of the body, heat insulating material surrounding the said sleeve, a container inside said sleeve and having its upper end opening through the top plate, said container being of diameter less than the diameter of the said sleeve and to provide a 50 closed air space between the container and the sleeve and a closure lid for the container.

5. A fireless stove, comprising a box shaped body, a top plate, an open sleeve extending from the bottom plate to the underside of the top plate of the body, heat insulating material surrounding the said sleeve, a container inside said sleeve and having its upper end opening through the top plate, 55 said container being of a diameter less than that of the sleeve to provide a closed air space between the container and the sleeve, a closure lid of hollow construction and having a resilient bottom plate, stuffing for the interior of the lid to maintain the bottom plate of the lid at normally bulged position, and a clamping means to draw the lid to tightened engagement with the top plate of the box so that the surface of the said top 70 plate immediately surrounding the rim or mouth of the container is sealed.

In testimony whereof I affix my signature in the presence of two witnesses.

GEORGE A. TAYLOR.
